UNITED STATES PATENT OFFICE

148,825

DESIGN FOR A WASTE RECEPTACLE

Arthur Melville Snider, Waterloo,
Ontario, CanadaApplication March 8, 1946, Serial No. 127,261
In Canada September 13, 1945

Term of patent 14 years

(Cl. D58—4)

To all whom it may concern:

Be it known that I, Arthur Melville Snider, a subject of the King of Great Britain and resident of the town of Waterloo, county of Waterloo, Province of Ontario, in the Dominion of Canada, have invented a new, original, and ornamental Design for a Waste Receptacle, of which the following is a specification, reference being had to the accompanying drawings, forming part thereof.

Figure 1 is a perspective view of a waste receptacle showing my new design.

Figure 2 is a perspective view thereof showing the lid in open position.

I claim:

The ornamental design for a waste receptacle, substantially as shown.

ARTHUR MELVILLE SNIDER.
